CARD GAME

Application filed June 4, 1927. Serial No. 196,536.

This invention relates to card games and more particularly to a game in which the cards bear characteristic data of distinctive value whereby original, unique, and instructive games combining skill and chance may be devised.

A primary object of the invention is to provide a card game consisting of a deck of cards composed of a number of different suits, which may be employed to play various highly amusing and interesting games and which at the same time involve sufficient "fine points" to render attention, alertness and resourcefulness, a large factor in the success of the game.

Another object is to provide a deck of cards each card of which possesses a taking and a score value.

In carrying out these objects the invention is susceptible of modification without departing from the spirit or sacrificing any of the advantages of the claimed invention, there being shown in the drawing for illustrative purposes, a preferred and practical form in which a single suit is shown composed of thirteen cards.

The game is ordinarily played with a single deck of fifty-two cards consisting of four suits having thirteen cards in each. All of the cards are preferably white on their faces with the numbers employed in connection therewith printed in distinctive colors, that is, the numbers of each suit are printed in a different color, there being four colors for the four suits. The backs of the cards may be of any desired design. In the embodiment illustrated a single suit is shown composed of thirteen cards on the playing faces of which at diagonally opposite corners are inscribed or printed two figures or numerals at each of said corners, one arranged above the other, and in a sequence presently to be described. These cards of the suit shown are numbered from 1 to 13 respectively and are exactly alike except for the indicia on the faces thereof. The diagonally opposite pairs of numerals carried by each card are disposed at the upper left hand corner and the lower right hand corner respectively, and the upper numerals which represent taking

values of the cards while the lower numbers represent score values. The numerals on all of the cards of each suit are of the same color, the colors of the different suits varying. The upper or taking value numerals indicated at 55 14 increase successively on the respective cards of the suit, that is, card 1 bears the numeral 1 at the upper left hand corner and at the lower right hand corner while card 2 bears the numeral 2, and 3 the numeral 3, 60 and so on. The score value numerals designated 15 which are the lower numbers of the pair decrease successively the card numbered 1 bearing the score numeral 12 and card 2, 11, and card 3, 10 and so on, down through the series. It will be understood from the foregoing description that I have provided a set of cards for a game consisting of a plurality of groups having identifying means distinguishing the groups among themselves, 70 the cards of a group each bearing a numerical designation of a capturing power value defining a serial arrangement in the group, which serial arrangement extends throughout the group, and a separate numerical designation of a counting value defining a different serial relation, said different serial relation also extending throughout the group. It will be observed that the separate numerical designation of a counting value defines a reverse 75 serial relation with respect to the serial arrangement used to indicate the capturing power value. It will also be observed that the capturing power values and the counting value are complementary.

This develops an unusual and novel situation in that the trump card of lowest capturing power results in the greatest counting value if said card of lowest capturing power prevails, and this is true, in a known decreasing ratio or scale, with respect to the whole series of cards. A player may therefore maneuver to have cards played which are of large capturing power but of small counting value, in the hope that plays will develop in which all that are left are cards of small capturing value, but of great counting value. He may follow suit but retain, if possible, trump cards of low capturing value, such as the "1" or "2", knowing that ultimately he 85 90 95 100

may be able by a trump play of the "1" or the "2", for example, to take a hand when all others have exhausted trumps and thus score heavily.

5 Four persons ordinarily play the game which constitute one table, opposites playing partners. The cards are dealt thirteen to each person and when bidding, each player may or may not, as agreed upon in advance announce the color bid on. If agreed upon in advance, each player may or may not, as he chooses, after the highest bidder has named the trump, select blindly one card from the hand of any or all other players at his table 10 allowing in exchange one from his hand selected blindly. After such exchanges are completed, or, if none are desired, playing will begin.

In playing the game in the manner herein set forth, with the upper numbers representing the taking values of the cards and the lower numbers the score values only trump card score values are counted, and the players must follow suit if possible. If no suit card 20 is held, any other card may be played. A trump card, of course, is superior to any non-trump card, and the dealer bids first, followed by the player at the left. Two bids only are allowed each player and the minimum bid 25 allowed may be forty or any other number named, as agreed upon. The highest bidder names the trump by color and the player at his left leads.

The score for each hand is as follows:

30 Count the lower figures of all trump cards taken, there being thirteen cards of each color having a combined score value of seventy-eight, add three for each trick taken over six, then add ten if all trumps are taken. If all 35 tricks are taken fifteen is added to the score and if the high bidder fails to score the full amount of his bid is charged against him, or rather deducted from his score. The game 40 may consist of four hands or they may continue to play until a signal is given, when each individual will total his score and the 45 reward given to the highest.

The lowest card of the series, or the one numbered 13 has the numeral 13 as the taking 50 value of the card and below it a naught or cipher, so that this card has no score value unless it is agreed by the players to give it a certain value.

Without further description it is thought 55 that the features and advantages of the invention will be readily apparent to those skilled in the art, and it will of course be understood that changes in the form, proportion and minor details of construction may be resorted to, without departing from the 60 spirit of the invention or its scope as claimed.

I claim:—

65 1. A set of cards for a game consisting of a plurality of groups having identifying means distinguishing the groups among

themselves, the cards of a group each bearing an actual numerical designation of a capturing power value defining a serial arrangement in the group, which serial arrangement extends throughout the group, 70 and a separate actual numerical designation of a counting value defining a reverse serial relation, said different serial relation extending throughout the group.

2. A set of cards for a game consisting of 75 a plurality of groups having identifying means distinguishing the groups among themselves, the cards of a group having a serial relation and each bearing actual numerical designations of a capturing power value and of a counting value, said numerical values being complementary whereby the counting value of a card increases as its capturing value decreases, the numeral designation both of capturing power and counting 80 value extending throughout each group. 85

3. A set of cards for a game consisting of 90 four groups each having thirteen cards, said groups having identifying means distinguishing the groups among themselves, the cards of each group each bearing an actual numeral designation of a capturing power value defining a serial arrangement in the group and extending serially from one to thirteen inclusive, and the cards of each group also having a separate actual numeral designation of a counting value, said numerical 95 designations extending in a reverse order, serially from twelve to zero inclusive.

4. A set of cards for a game consisting of 100 four groups having identifying means distinguishing the groups among themselves, the cards of each group each bearing an actual numerical designation of a capturing power value defining a serial arrangement in the group, said serial arrangement consisting of consecutive and therefore non-duplicated numbers throughout each group, and a separate 105 actual numerical designation of a counting value defining a reverse serial relation, said reverse serial relation consisting of consecutive non-duplicated numbers throughout the group. 110

5. A set of cards for a game consisting of 115 four groups, each having thirteen cards, and the groups having identifying means distinguishing the same from each other group, the cards of each group each bearing an actual numerical designation of a capturing power value defining a serial arrangement in the group, said serial arrangement consisting of consecutive and therefore non-duplicated numbers throughout each group, and a separate 120 actual numerical designation of a counting value defining a reverse serial relation, said reverse serial relation consisting of consecutive non-duplicated numbers throughout the group. 125

6. A set of cards for a game consisting of 130 four groups having identifying means dis-

tinguishing the groups among themselves, the cards of each group each bearing arabic numerals constituting a designation of a capturing power value, said arabic numerals being consecutive and therefore non-duplicated throughout the group, the cards of each group also bearing separate arabic numerals each constituting a designation of a counting value, said arabic numerals being consecutive and therefore non-duplicated throughout the group, said two series of arabic numerals in each group being the reverse of each other.
